(57) **CLAIM**

The new and ornamental design for a horse lick support, as shown and described.

DESCRIPTION

FIG. 1 is a perspective view of a horse lick support showing our new design and wherein a basin or bowl is illustrated in dashed lines,

FIG. 2 is a perspective view thereof without the bowl,

FIG. 3 is a left side elevation thereof, the right side elevation being a mirror image of FIG. 3,

FIG. 4 is a top plan view thereof,

FIG. 5 is a front elevation thereof; and,

FIG. 6 is a bottom plan view thereof.
